(57) **CLAIM**

The ornamental design for a food tag, as shown and described.

DESCRIPTION

FIG. 1 is a top plan view of a food tag showing my new design;

FIG. 2 is a front elevational view thereof, the rear elevational view being a mirror image thereof;

FIG. 3 is a bottom view thereof; and,

FIG. 4 is a side elevational view thereof, the opposite side being a mirror image thereof.

The broken line showings form no part of the claimed design.
